United States Patent [19]

Bernardini

[11] Patent Number: Des. 434,206

[45] Date of Patent: ** Nov. 28, 2000

[54] SLIPPER

2,509,423 5/1950 Cramer 36/19.5
5,339,542 8/1994 Kim ..... 36/7.5[75] Inventor: **Marcello Bernardini**, Lucca, Italy

Primary Examiner—Louis S. Zarfas

[73] Assignee: **Pro. Media S.r.l.**, Lucca, Italy

Assistant Examiner—Gregory Andoll

[**] Term: 14 Years

Attorney, Agent, or Firm—Browdy and Neimark

[21] Appl. No.: 29/118,305

CLAIM

[22] Filed: Feb. 8, 2000

The ornamental design for a slipper, as shown and described.

[51] LOC (7) Cl. 02-04

DESCRIPTION[52] U.S. Cl. D2/919, D2/916; D2/949;
D2/973; D2/927; D2/897

FIG. 1 is a front perspective view of the slipper according to the invention;

[58] Field of Search D2/896, 897, 900,
D2/905, 916-931, 935, 948-960, 969-973,
978; 36/84, 7.5, 9 A, 10, 45, 47, 11.5, 19.5,
169, 166

FIG. 2 is a left side view of the slipper of the invention, the right side view being a mirror image thereof;

FIG. 3 is a front view thereof;

FIG. 4 is a rear view thereof;

FIG. 5 is a top plan view thereof; and,

FIG. 6 is a bottom plan view thereof.

The novel feature of the slipper according to the invention consists in that the sole is of reduced length and the rear end of the sole is rounded.
